UNITED STATES PATENT OFFICE

RAYMOND L. GILLISPIE, OF STEELTON, PENNSYLVANIA, ASSIGNOR TO BETHLEHEM STEEL COMPANY, A CORPORATION OF PENNSYLVANIA

RAILWAY-TRACK STRUCTURE

Application filed July 13, 1929. Serial No. 377,943.

My invention relates to joint or filler blocks for railway track structures and particularly to the type which engages the fishing surface of adjacent rails.

In connection with certain designs of railway frogs, switches, etc., it is necessary to provide a joint or filler block for connecting the adjacent running rails where there is insufficient room for splice bars or fish plates and where it is desired to provide a stiffer connection than can be obtained with splice bars or fish plates.

Heretofore it has been the practice to provide cast blocks for use with such frogs, switches, etc., but the objection to this type of block is that it is heavy, cumbersome, and not particularly strong.

It is therefore the object of my invention to provide a joint or filler block which is considerably lighter and more serviceable than the cast block heretofore used and which is easily manufactured.

The novel features of my invention will be more fully understood from the following description and claims taken with the drawings in which:

Fig. 1 shows a track structure embodying my invention in connection with a switch rail.

Fig. 2 is an enlarged top plan view of a section of the track structure embodying my invention.

Fig. 3 is a cross-section of my invention taken along lines 3-3 of Fig. 2.

Referring to the drawings, wherein I have shown my invention used in connection with a switch rail of a track structure, 10 designates the main rails, 11 the lead rails and 12 the switch rails. The switch rails 12 abut the lead rails 11 and are held in the proper alignment therewith by means of my improved joint block 13 which engages the fishing surface of these rails. The joint block 13 also engages the fishing surface of the main rail 10 and through suitable fastening means the lead rail 11 and the heel of the switch rail 12 are held in a substantially positive position relative to the main rail 10. The points 14 of the switch rails 12 are connected in the usual manner by one or more tie

bars 15 and are capable of free movement on the slide plates 16, which are connected to the ties 17.

My improved block 13 comprises a forged member 18 which is substantially U-shape in cross section and a strengthening member 19 which is preferably a plate member. The member 19 is preferably placed within the U-shape member 18 so as to engage the sides 20 and 21 thereof a substantial distance below the top of the U-shape member in order to provide adequate space so that the flanges of car wheels will not come into contact with the member 19 during their passage over this member. The member 19 is preferably welded to the member 18 in any known manner.

Holes 22 are provided in the U-shape member to receive bolts 23, which pass through corresponding holes in the main rail 10 and the lead rail 11 or the main rail 10 and the switch rail 12 and which are adapted to retain the rail in their proper relation. The block 13 is counterbored at 24 so as to provide means for receiving the end of pipe collar 25 which fits loosely within the corresponding hole in the switch rail 12. The pipe collar 25 extends outside the switch rail 12 so as to allow a slight lateral movement of the switch rail before it is arrested by coming into contact with the head of the bolt 23 when the switch point 14 is moved from its normal position.

While I have shown my invention used in connection with a switch it can be used equally as well in connection with frogs, guard rails, etc., where it is advantageous to use a filler or joint block.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described my invention what

I claim as new and desire to secure by Letters Patent is:

1. A block for a railway track structure comprising a forged member adapted to engage the fishing surface of adjacent rails and a plate member for strengthening said forged member intermediate its extremities.
2. A joint block for a railway track structure comprising a forged member and a strengthening member extending longitudinally of the forged member and welded thereto.
3. A joint block for a railway track structure comprising a forged member of substantially U-shape in cross section and a plate member having its surface in a plane substantially parallel to the upper surface of the U-shaped member and welded thereto.
4. A block for a railway track structure comprising a U-shape forged member, a strengthening member intermediate the sides of the U-shape member in a plane substantially parallel to the upper surface thereof substantially throughout its length and means constituting a weld for securing the aforesaid members together.
5. In a railway track structure, a main rail, a lead rail, a switch rail, and a joint block intermediate the main rail and the switch and lead rails, said block comprising a forged member, a strengthening member for strengthening said forged member intermediate its extremities, and means for securing said members together.
6. The method of making a hollow block for a railway track structure which consists in forging a substantially U-shape member, forming a plate member, and welding the members together intermediate their extremities.
7. In a railway track structure, a main rail, a lead rail, a switch rail, and a joint block for spacing the last two mentioned rails from the main rail, said block comprising a U-shaped member and a plate member disposed between the legs of said U-shaped member in a plane substantially parallel to the upper surface of the U-shaped member and joined thereto.
8. A joint block for spacing railway track rails, comprising a U-shaped elongated member, and a plate member disposed between the legs of said U-shaped member substantially throughout its length and joined thereto.
9. A joint block for spacing railway track rails, comprising a U-shaped member, and a plate member disposed between the legs of said U-shaped member substantially throughout the length of the U-shaped member and joined thereto at a distance from the outside marginal edges thereof.
10. A joint block for spacing and connecting railway track rails, comprising an elongated forged member having one side

adapted to engage the fishing surface of a main rail and another side adapted to engage the fishing surfaces of a switch rail and a lead rail and a plate member adapted to strengthen the forged member at the junction of the switch rail and the lead rail.

In testimony whereof I hereunto affix my signature.

RAYMOND L. GILLISPIE.
